UNITED STATES PATENT OFFICE.

JOHN MASSEY, OF ANDERSON, INDIANA.

ELECTRIC MOTOR OR ENGINE.

SPECIFICATION forming part of Letters Patent No. 726,177, dated April 21, 1903.

Application filed December 2, 1901. Renewed December 10, 1902. Serial No. 134,705. (No model.)

To all whom it may concern:

Be it known that I, JOHN MASSEY, a citizen of the United States, and a resident of Anderson, in the county of Madison and State of Indiana, have made a certain new and useful Invention in Electric Motors or Engines; and I declare the following to be a full, clear, and exact description of the same, such as will enable others skilled in the art to which it appertains to make and use the invention, reference being had to the accompanying drawing, and to letters of reference marked thereon, which forms a part of this specification.

The drawing shows the invention as applied, 15 the motor being in side elevation.

The invention has relation to electric motors or engines; and it consists in the novel construction and combinations of devices, as hereinafter set forth.

20 In the accompanying drawing the letter *a* represents the working shaft of the engine, having a fly-wheel *b* and a crank *c*, which is connected by means of a pitman *d* to a reciprocatory armature-rod *e*, for which guide bearings or perforations *g* are provided in the opposite standards of the frame *h*, to the ends of which are secured the electromagnets *k* and *k'* within said frame *h*. These electromagnets have their cores in alinement and 25 are connected to the battery or source of electricity *m* by wiring. The armature between the electromagnets is an arm or plate *p*, carried by the bar *e* and which projects between the oppositely-facing ends of these magnets. 30 This armature is rigidly connected to said bar *e* and at its end engages the fork at the end portion of a shifting lever *q*, which is intermediately pivoted to the framing and has its opposite end portion in sliding contact with 35 the terminal contacts *s* and *s'* of the switch, which are disconnected from each other, but have their ends in approximation. A binding-post *t* is also connected to the framing. These parts—that is to say, the switch-lever 40 *q*, the switch-bearings, and the wire connection *t*—are all properly insulated. The wiring of the electromagnet *k'* is indicated at *w'* and that of the magnet *k* at *w*. One terminal of

the wiring *w'* is connected to the switch-bearing *s'*, and the other terminal of said wiring 50 is connected to the binding-post *t*. One terminal or energizing wire *z* of the battery is connected to the common binding-post *t*, while the other terminal wire, *z'*, of said battery is connected with the arm *r* of the switch-lever *q*. 55

The operation is as follows: The switch-lever being on the switch-contact *s*, the electromagnet *k* is energized to move the armature *p*, the bar *e*, and the crank of the engine and the fly-wheel. As this rotary motion continues 60 through the momentum of the fly-wheel the armature *p* is moved in the opposite direction and disengaged from the contact *s*, engaging the bearing *s'*, so that the electromagnet *k'* becoming energized draws the armature in the opposite direction and controls 65 the movement of the bar *e*, crank, fly-wheel, and operating-shaft.

This engine is mainly designed for use in operating toys and light moving machinery. 70

Having thus described my invention, what I claim as new, and desire to secure by Letters Patent, is—

In an electric motor or engine, the opposite perforated standards, the opposite electromagnets within said standards, and having their cores in alinement, the reciprocatory armature-rod engaging the perforations of said standards, the driven shaft having an operating connection with said rod, the armature rigidly affixed to said rod, the terminal contacts, the terminal post, the intermediately-pivoted switch-lever having an operating connection with said armature at one end thereof, and adapted to engage said contacts 85 at the opposite end portion thereof, and the electric battery having terminal connections with said lever and post, said magnets having terminal connections with said post and contacts, substantially as specified. 90

In testimony whereof I affix my signature in presence of two witnesses.

JOHN MASSEY.
